(57) **CLAIM**

The ornamental design for a tissue cell block for cancer detection, as shown and described.

DESCRIPTION

FIG. 1 is a top perspective view of a tissue cell block for cancer detection showing our new design; FIG. 2 is a top plan view thereof, the bottom plan view being a mirror image thereof; and, FIG. 3 is a side view thereof.

Area depicted in dense stippling represents a color and cell type different than area depicted in spare stippling. Area depicted in spare stippling represents a color on an opaque background.
